PAGE 2

FIG. 2

FIG. 3

FIG. 4

FIGURE 1 is a perspective view of a jug with bottle receiving pockets for packaging purposes showing our new design;

FIGURE 2 is a top plan view thereof;

FIGURE 3 is a side elevational view thereof on a reduced scale; and

FIGURE 4 is a perspective view thereof taken from the side opposite that shown in FIGURE 1 on a reduced scale.

The dominant features of our design reside in the portions shown in full lines. The small bottles shown in broken lines are for illustrative purposes only.

We claim:

The ornamental design for a jug with bottle receiving

pockets for packaging purposes, substantially as shown and described.
